BRAKE SHOE

Hugh G. Margetts, Leamington Spa, and Gordon A. Habgood, Shipston-on-Stour, England, assignors to Girling Limited, Tyseley, England

Filed Aug. 11, 1969, Ser. No. 18,613

Claims priority, application Great Britain Feb. 27, 1969

Term of patent 14 years

Int. Cl. D12—14

U.S. Cl. D14—30

Fig. 1 -

Fig. 2 -

FIG. 1 is a side elevation of a brake shoe showing my new design, the opposite side being a mirror image;

- * FIG. 2 is a plan of the brake shoe;
- FIG. 3 is an inverted plan of the brake shoe;
- FIG. 4 is an end elevation of the brake shoe;
- FIG. 5 is an elevation of the opposite end thereof;
- FIG. 6 is a section on line 6—6 of FIG. 1, and
- FIG. 7 is a section on line 7—7 of FIG. 1.

We claim:

The ornamental design for a brake shoe, as shown and described.
